MARINE CLOCK

Filed June 6, 1923

UNITED STATES PATENT OFFICE.

FREDERICK WEHINGER, OF WATERBURY, CONNECTICUT, ASSIGNOR TO WATERBURY CLOCK CO., OF WATERBURY, CONNECTICUT, A CORPORATION.

MARINE CLOCK.

Application filed June 6, 1923. Serial No. 643,612.

To all whom it may concern:

Be it known that I, FREDERICK WEHINGER, a citizen of the United States, residing at Waterbury, in the county of New Haven and State of Connecticut, have invented a new and useful Improvement in Marine Clocks; and I do hereby declare the following, when taken in connection with the accompanying drawings and the characters of reference marked thereon, to be a full, clear, and exact description of the same, and which said drawings constitute part of this application, and represent, in—

Fig. 1 a view, mainly in front elevation, but partly in broken, vertical section, of a marine clock embodying my invention.

Fig. 2 a view of the clock in vertical, central section, barring the clock-movement, which, stripped of its train, is shown in elevation.

Fig. 3 a detached, perspective view of the lower bracket of the case-back.

Fig. 4 a corresponding view of the upper bracket thereof.

My invention relates to an improvement in so-called marine clocks, the object being to produce, at a low cost for manufacture, a simple, compact and convenient clock of the character described, constructed with particular reference to convenience of assembling and rigidity of structure when put together.

With these ends in view, my invention consists in a marine clock having certain details of construction and combinations of parts as will be hereinafter described and particularly pointed out in the claims.

In carrying out my invention, as herein shown, I employ a relatively deep, cup-shaped case-back 5 having, upon its forward edge, a wide, annular flange 6 located in a plane parallel with the plane of the back of the case-back and itself formed with a rearwardly-turned, narrow, annular fitting-rim 7. The said case-back provides for the carriage or mounting of the movement, whatever the detailed construction of the same may be. As herein shown, the movement is, for convenience of illustration, limited to its main structure, consisting of front and rear movement-plates 8 and 9, held together by pillars 10 and 11, the rear ends of which are provided with threaded stems 12 passed through suitable perforations in the back of the case-back 5 and receiving nuts 13, by

means of which the movement is rigidly secured to the case-back, by which its rear portion is enclosed.

To the front face of the lower portion of the flange 6 of the case-back 5 I secure a segmental lower bracket 14, formed at its ends with corresponding mounting-arms 15 turned forward from its lower edge at a right angle to its plane and having threaded perforations 16. The said bracket is also formed with a wide, clock-supporting arm 17 extending rearwardly at a right angle to its plane, from the center of its lower edge, through a narrow slot 18 in the lower edge of the flange 6. As shown, the bracket 14 is secured to the front face of the flange 6 of the case-back 5 by means of fastening-fingers 19 struck out of it and passed through holes in the said flange and headed down upon the rear face thereof, but I do not limit myself to any particular means for rigidly attaching the segmental bracket in question to the case-back.

The threaded perforations 16 of the respective mounting-arms 15 receive the threaded stems 21 of two case-legs 22, which are passed through suitable perforations 23 located on opposite sides of the center of the bottom of the case-body 24, which is adapted in diameter to fit over the arms 15, as well as over the mounting-arm 25 of an upper bracket 26 secured by integral fingers 27 to the upper edge of the front face of the flange 6 of the case-back, the rim 7 whereof fits snugly within the case-body, which is virtually sleeved over the said case-back.

By means of the upper and lower brackets secured to the case-back, as described, the case-body is firmly attached to the case-back, by which, as already described, the movement is carried.

The rearwardly-extending, clock-supporting arm 17 provides, as it were, a third leg for the clock, which is supported in a tilted position by means of this arm, in conjunction with the two case-legs 22 located in a plane in front of it.

The handle of the clock consists of a ring-head 28 mounting a ring 29 and having a threaded stem 30, which passes downward through a perforation 31 in the top of the case-body and enters a threaded hole 32 in the mounting-arm 25 of the upper bracket 26.

As herein shown, but having nothing to do

with my present invention, a flanged bell 33 is secured to the case-back by means of screws 34 entering a reinforcing washer 35 located within the case-back, which is formed with 5 a central opening for the rearward projection through it of the center-arbor 36, which is provided at its rear end with an operating-button 37 and at its forward end with the minute-hand 38.

10 The front movement-plate 8 mounts a dial-back 39 carrying a dial 40, which is enclosed by a mat 41 co-acting with the inwardly-turned, forward edge of the case-body 24 in holding the glass 42 in place.

15 It will be understood from the foregoing that under my invention the case-back provides for mounting and carrying the clock-movement and the adjuncts thereof, and also for the attachment of the case-body, 20 which is secured to it by means of the case-legs and case-handle. This provides an exceedingly rigid clock-structure and one easily assembled and dismembered.

25 The lower bracket discharges the three-fold function of providing for the attachment of the case-legs; for securing the case-body to the case-back; and also for the support of the clock in the usual tilted position of such clocks.

30 I claim:

1. In a marine clock, the combination with a case-body, of a case-back adapted to be entered into the open rear end thereof; a clock-movement carried by the said case-back, a bracket fastened to the lower portion of the case-back, formed with a rearwardly-projecting arm providing a third support for the clock and with forwardly-projecting lugs located on opposite sides of the said rearwardly-projecting

arm and having screw-holes, threaded legs passing through perforations in the lower portion of the case-body into the said lugs, whereby the said legs are solidly mounted, the case-back and case-body secured together and a third support provided for the clock, and means for securing the case-body and case-back together at the top of the clock and furnishing it with a handle. 45

2. In a marine clock, the combination 50 with a case-body, of a case-back adapted to fit into the open rear end thereof, a clock-movement carried by the said case-back, a forwardly-projecting bracket fastened to the upper portion of the case-back and provided with a screw-hole, a bracket fastened to the lower portion of the case-back, having a centrally-arranged, rearwardly-projecting arm and two forwardly-projecting lugs located on opposite sides of the said 55 arm and having screw-holes, a threaded handle passing through the case-body into the screw-hole of the said upper bracket, whereby the said handle is solidly mounted, and the case-body and case-back are secured together at the top of the clock, and two threaded legs passing through perforations in the case-body into the screw-holes in the respective lugs of the lower bracket, whereby the said legs are solidly mounted, the 60 lower portions of the case-body and case-back secured together and a third support provided for the clock.

65 In testimony whereof, I have signed this specification in the presence of two subscribing witnesses.

70 FREDERICK WEHINGER.
